DESIGN FOR A SUCTION HAIR DRIER

Clyde S. Morse, Sycamore, Ill.

Application November 1, 1934, Serial No. 53,845

Term of patent 3½ years

To all whom it may concern:

Be it known that I, Clyde S. Morse, a citizen of the United States, residing in Sycamore, De Kalb County, Illinois, have invented a new, original, and ornamental Design for a Suction Hair Drier, of which the following is a specification, reference being had to the accompanying drawing, forming a part hereof.

I claim:

The ornamental design for a suction hair drier substantially as shown.

CLYDE S. MORSE.
